UNITED STATES PATENT OFFICE.

JAMES EDWARD BROPHY AND WILLIAM E. HARVEY, OF WASHINGTON,
DISTRICT OF COLUMBIA.

DESIGN FOR A BADGE OR BANNER.

SPECIFICATION forming part of Design No. 18,486, dated July 31, 1888.

Application filed July 3, 1888. Serial No. 276,967. Term of patent 3½ years.

To all whom it may concern:

Be it known that we, JAMES EDWARD BROPHY and WILLIAM E. HARVEY, citizens of the United States, residing at Washington, District of Columbia, have invented and produced a new and original Design for a Campaign Badge; and we do hereby declare the following to be a full, clear, and exact description of the invention, such as will enable others skilled in the art to which it appertains to make and use the same.

The drawing shows a front view of the design set upon a background of silk, paper, or other material in suitable colors; and the leading feature of the design consists in the badge or banner having thereon the representation of a log cabin upon the front face of the background, immediately below the representation of the well-known Grand Army badge or medal.

A is a shield having in its upper field the

stars and in its lower the stripes. In the upper portion of this shield are two portrait spaces or openings, *a*, between which is set a representation of the Grand Army badge B. 25

E is the representation of a log cabin occupying the middle or central portion of the lower field.

The shield is surmounted by a scroll, and underneath the shield are arranged three long 30 chain-links.

We claim—

The design for a campaign badge or banner having the surface ornamentation herein described and shown. 35

In testimony whereof we affix our signatures in presence of two witnesses.

JAMES EDWARD BROPHY.
WM. E. HARVEY.
